COUPLED HELICAL WAVE STRUCTURE EMPLOYING A REMANENTLY MAGNETIZED FERRITE

Ivars G. Akmenkalns, Endicott, and Philip A. Lord, Vestal, N.Y., assignors to International Business Machines Corporation, Armonk, N.Y., a corporation of New York
Filed Dec. 30, 1965, Ser. No. 517,629

10 Claims. (Cl. 333—24.1)

This invention relates in general to coupled helical wave structures and, more particularly, to a plurality of helical wave structures operating on the principle of gyro-magnetic resonant absorption and a ferrite toroid as the means for controlling the transmission of a microwave signal from a first helical structure to a second helical structure.

It is generally well known that microwave energy can be absorbed by the ferrite material of a microwave structure if the proper conditions for gyro-magnetic resonant absorption are created. The term ferrite is used to refer to that class of magnetic metals which possess extremely high resistivity and permeability. More specifically, the proper conditions include the switching of the ferrite element into its state of magnetization so that one electron in the ferrite finds itself in the field of all the other electrons. That is, the one electron is not free to move alone in response to an external magnetic field because of exchange interactions but rather, must respond to the external magnetic field together with its neighboring electrons. Because this type of electron has both a magnetic moment and angular momentum, it acts like a small magnetized top when exposed to an external magnetic field. When the electron is in this external magnetic field, the field attempts to rotate the electron so that the two become aligned. Like all tops upon which such forces act, however, the electron does not line up with the field but instead precesses or swings about the field direction. With a magnetic field which is rotating in the same sense as the electron precesses, the electron absorbs energy from the field and tends to become disaligned therefrom. This process of the precessing electron tending to absorb energy from an external field is generally known as gyro-magnetic resonant absorption. When the external magnetic field is rotating in a sense opposite to that in which the coupled electrons are precessing or the magnetic field is oscillating at a substantially different rate of rotation, the magnetic field passes through the ferrite substantially undiminished in intensity.

It is an object of the instant invention to provide a coupled helical wave structure employing a ferrite element as a shielding means for switchably controlling the coupling of microwave signals from a first helical coil to a second helical coil.

It is a still further object of the instant invention to provide a coupled helical wave structure which operates similarly to a transformer.

It is another object of the instant invention to provide a coupled helical wave structure which is capable of use as a direction coupler.

These and other objects of the instant invention are accomplished by the present invention through the use of a cylindrical ferrite element having a central bore. A drive wire threads the bore for switching the element to either of its stable states of remanent magnetization. A first coil is wound on the outer surface of the ferrite element, and a second coil is placed within the central bore. While the ferrite is in one state of remanent magnetization, microwave energy is coupled from the first coil to the second. While the ferrite is in its second state of remanent magnetization, the coupling is substantially reduced.

The foregoing and other objects, features and advan-

2

tages of the invention will be apparent from the following more particular description of preferred embodiments of the invention, as illustrated in the accompanying drawings, wherein

5 FIG. 1 is a partial section taken on the center line of the ferrite element showing the placement of the inner coil;

10 FIG. 2 is a standard BH curve associated with magnetic material;

15 FIG. 3 shows an alternate embodiment of the instant invention wherein the leads to the inner coil pass through the ferrite element; and

20 FIG. 4 shows the placement of the inner coil away from the ends of the ferrite element.

25 The same numerals are used to identify similar items in each of the several views.

30 Referring to FIG. 1, there can be seen a cylindrically shaped ferrite element 2 having an outer wall 4 and an inner wall 6. The inner wall 6 forms a central bore 8 through which a drive wire 10 and a first helical coil 12 are placed. The drive wire 10 transmits bi-polar switching pulses from a signal source 13 to switch the ferrite element to either of its two remanent states of magnetization. The coil 12 is shown having a right to left pitch and having a constant distance 14 between adjacent turns, however, the direction and pitch is not critical to the operation of the instant invention. The coil 12 has a slightly greater diameter than the diameter of the bore 8 and the coil is made of resilient material. The coil 12 is drawn slightly, inserted in the bore and then released to regain its original shape. The coil then holds the element 2 in a fixed position. An air gap can exist between the coil 12 and the ferrite 2 if an alternate method of securing 12 and 2 together is employed. An end 16 35 of the coil 12 is connected to a first detector 18, and the remaining end 20 is connected to a utilization means 22. The device has been found to operate better when no portion of the coil 12 extends beyond the ends 19 and 19a of the element 2. The utilization means 22 can be 40 a strip line, another detector or any device in general.

45 A second helical coil 24 is wound around the outer wall 4 of the element 2, which coil is shown having a left to right pitch opposite to that of the coil 12. A certain direction and pitch of the coil 24 has not been found critical to the operation of the instant invention. An end 26 of the coil 24 is connected to a source of microwaves 28 by a strip line and the remaining end 28a is 50 connected to a second primary detector 29. The device has been found to operate better when no portion of the coil 24 extends beyond the ends 19 and 19a of the element 2.

55 In operation, the coupled helical wave structure is selectively switched to either of its remanent states of magnetization. FIG. 2 shows a standard BH magnetization curve having its two remanent states identified as 30 and 32. Assuming the element is driven to its first remanent state 30 by a positive going pulse on the drive wire 10, the electrons in the ferrite are circularly polarized and given a first sense of rotation. Additionally, the microwave source is activated sending a microwave signal down the helix 24. The helix causes the signal to generate a highly circularly polarized magnetic field, also rotating in the first sense of rotation. Since the microwave frequency is designed to match the gyro-magnetic resonant absorption frequency of the ferrite, coupling between the electrons and the field occurs and the field is partially absorbed by the ferrite to reduce the coupling of the microwave signal to the helix 12. A first level of microwave energy is sensed in the utilization means 22. The primary detector 29 senses a reduced level of microwave energy transmitted from the oscillator 28. This reduction is 60 65 70

attributed to absorption in the ferrite and coupling to the coil 12.

When the element is driven to its second stable state of remanent magnetization, its electrons are caused to rotate in a second sense of rotation. The helix continues to generate a field rotating in a first sense of rotation so no coupling occurs. The magnetic field penetrates the ferrite and is picked up by the inner coil 12 and sensed by the utilization means 22. When the ferrite is in that state increased transmission to the utilization means is observed since less absorption occurs. The signal level at the utilization means is increased approximately 20 db. As between the ends 16 and 20 of the inner coil 12, maximum power is available at the end 16.

FIG. 4 shows the ends 16 and 20 of the inner coil 12 spaced from the ends 19 and 19a of the element 2. FIG. 3 shows the ends 16 and 20 of the inner coil 12 being connected to the detector 18 and the utilization means 22 respectively by wires 34 and 36 respectively passing through the walls 4 and 6 of the element 2 through passages 38 and 40 respectively.

The instant invention will satisfactorily operate when the element 2 is premagnetized prior to its assembly into a completed coupled helical wave structure. In this embodiment a drive wire 10 need not be supplied if the state of the element 2 is to remain unchanged.

In summary, the present invention is a four-terminal device having an additional drive line 10 available to switch the ferrite 2 to either of its stable magnetic states. A first helix 24 is wound around the outside of a circular ferrite core 2 and a second helix 12 is placed within a central bore 8 of the ferrite. A microwave oscillator 28 is applied to one end of the outer helix 24 and a primary detector 29 is attached to the second end of the helix 24. Different levels of microwave energy are sensed at the primary detector 29 depending upon the switched state of the ferrite 2. A detector 18, attached to the near end 16 of the inner helix 12, receives microwave energy which is substantially independent of the switching action of the ferrite 2. The utilization means 22 is connected to the opposite end 20 of the inner coil 12 which receives microwave energy dependent upon the switched state of the ferrite 2.

While the invention has been particularly shown and described with reference to preferred embodiments thereof, it will be understood by those skilled in the art that the foregoing and other changes in form and details may be made therein without departing from the spirit and scope of the invention.

What is claimed is:

1. A coupled helical wave structure comprising, a ferrite element having a bore positioned therethrough, said element having an integral gyromagnetic resonant absorption frequency, said element being selectively magnetized to a first stable state of remanent magnetization and to a second stable state remanent magnetization, said magnetized ferrite generating a first circularly polarized magnetic field having electrons with a first sense of rotation corresponding to a said first stable state of remanent magnetization and for generating a second circularly polarized magnetic field having electrons with a second sense of rotation corresponding to said second stable state of remanent magnetization, a source of microwave signals operating at substantially said resonant absorption frequency,

second means positioned around said element and connected to said source for circularly polarizing said microwave signal in said first sense of rotation, third means positioned within said bore for magnetically coupling with said microwave signal on said second means, and

said ferrite in said first state of remanent magnetization substantially absorbing said microwave signals in said ferrite and said ferrite in said second state of remanent magnetization substantially passing said microwave signals undiminished to said third means.

2. The coupled helical wave structure as recited in claim 1, wherein said element is premagnetized to said selected state of remanent magnetization.

3. The coupled helical wave structure as recited in claim 1, wherein said element is cylindrically shaped and is premagnetized to said selected state of remanent magnetization.

4. The coupled helical wave structure as recited in claim 1, and further including a cylindrically shaped inner wall which forms said bore and wherein said third means is positioned in contact with said inner wall.

5. The coupled helical wave structure as recited in claim 1, wherein said element is cylindrically shaped, said bore is centrally located within said element and is formed by an inner wall, and

said third means is in contact with said inner wall.

6. The coupled helical wave structure as recited in claim 5, wherein said element is premagnetized to said selected state of remanent magnetization,

and further including utilization means responsive to said third means.

7. The coupled helical wave structure as recited in claim 1 and further including drive means threading said bore for selectively magnetizing said element to the desired state of remanent magnetization.

8. The coupled helical wave structure as recited in claim 7, wherein said second means is positioned wholly in contact with said element.

9. The coupled helical wave structure as recited in claim 1, wherein said element is cylindrically shaped, said bore is centrally located within said element and is formed by an inner wall,

said third means is in contact with said inner wall, said element is formed with a plurality of passages connecting said central bore to external said element, and further including utilization means responsive to said third means, and

fourth means positioned within said passages for connecting said utilization means to said third means.

10. The coupled helical wave structure as recited in claim 1, wherein said second means is positioned wholly in contact with said element,

said third means comprises a helical coil having a plurality of turns, and

said turns comprising the ends of said coil being spaced from the ends of said element.
